UNITED STATES PATENT OFFICE.

EDWARD A. ROBINSON, OF MONTREAL, QUEBEC, CANADA, ASSIGNEE OF ONE-HALF TO HIMSELF AND ONE-HALF TO ELLISON EDWARD WORKMAN, OF MONTREAL, CANADA.

TERMINAL SLEEVE FOR TRAIN PIPES IN CONNECTER HEADS.

Application filed January 7, 1922. Serial No. 527,568.

My invention relates to pipes intended to be seated in the heads of automatic connectors, forming terminals of train pipes and intended for automatic coupling to corresponding pipes upon adjoining cars to form a through connection.

The purpose of my invention is to make the train pipe terminals within the heads removable from the heads for replacement 10 of gaskets while the heads are connected and the cars are coupled.

A further purpose is to form a long connection between the head and a removable abutment for the spring pressing the train 15 pipe terminal forward with respect to the head, so that the abutment can be backed off to withdraw the terminal and the parts may be replaced while the cars are coupled and the hose is connected with the train 20 pipe terminal.

A further purpose is to enclose the spring forcing the train pipe terminal forward in the connector head within a removable and 25 adjustable casing carrying an abutment for said spring so as to attain additional axial length of threaded connection between the parts without excessive thickness of head.

A further purpose is to provide the head with a removable engaging surface 30 rounding the train pipe terminal.

A further purpose is to make the engagement of separate parts of the head with the meeting parts of mating heads, in the positions corresponding to the individual train 35 pipe terminals, adjustable not only when the heads are disconnected but even when the heads are connected by reason of coupling of the cars.

Further purposes will appear in the specification and in the claims.

I have preferred to illustrate my invention by but one main form with several slight modifications thereof, selecting a form which is practical, efficient, inexpensive and readily adapted to a great variety of heads, and which at the same time well illustrates the principles of my invention.

Figure 1 is a side elevation showing one form of connector head and mounting therefor to which my invention is applicable.

Figure 2 is a broken longitudinal section through the head showing my invention applied thereto.

Figure 3 is a broken longitudinal section showing two opposed train pipe terminals 55 and their correlated parts with the abutment in retracted position, preliminary to removal or ready for tightening after replacement of the gaskets.

Figure 4 is a section corresponding to 60 Figure 3 and showing a slightly modified form.

Figure 5 is a corresponding section showing my removable abutment extended 65 through the head to make adjustable that part of the head surrounding the gasket.

In the drawings similar numerals indicate like parts.

In order to illustrate the fact that my invention is used in conjunction with connector heads which are normally mounted in some manner resiliently from brackets to relatively fixed train parts, I have shown one form of such head and mounting, 70 though recognizing the fact that the particular form of the head and mounting have nothing to do with the present invention except as the shape of the head or the location of the connections with respect to it may cooperate with the structure of the retaining devices for the terminals to assist in application of the invention or by their shape or location may interfere with the use of or accessibility of the parts comprising 75 my invention.

Describing the general structure of Figure 1, therefore, without claiming this structure, and viewing it as for my purpose a generic mount, though it is described and claimed in an application filed by Edward A. Robinson, for automatic train pipe connectors, Ser. No. 255,948, filed February 3, 1920, I show a bracket 10 having at its lower end a threaded split clamp 11 tightened by bolt 12 about a helical spring 13 which is gripped within the threads of the clamp. This spring 13 is correspondingly threaded into and gripped by a split clamp 14 tightened by bolt 15 embracing the outer end of the spring.

The split clamp 14 forms part of a support, here shown as of yoke form, and comprising arms 16 and 17 terminating at different heights and staggered laterally so as to lie on opposite sides of the head 18 and be bolted to it at 19. The ends of the yoke

arms abut against flanges 20 upon the rear of the head so as to relieve the bolts from shearing thrust. The head is provided with the usual ears 21, staggered to cooperate with the corresponding ears and head of a mating connector.

The head 18 may be of any shape to suit the needs or whim of the designer. I have shown it in convenient form, as comprising 19 three generally cylindrical train-pipe-receiving bosses or body portions 22, 23 and 24 connected by webs 25 and 26. In addition the body portions 22 and 23 are connected at the side by a fin 27 supporting one of the 25 ears and the body portions 23 and 24 are connected on the opposite side by a fin 28 supporting the other ear. The webs 25 and 26 on the opposite sides from the ears carry the slight lateral flanges 20 which pass the 29 thrust of the head to the yoke arms 16 and 17.

The body portions are shown as three in number in the illustration because this corresponds with the maximum number of train 25 pipes to be connected in actual service, three being used normally for passenger service and one or two being used for freight service. As will be seen my invention is applicable to either of the other types of service 30 by reducing the number of body portions but without requiring any change in the construction by which the gaskets may be replaced in service without uncoupling.

Whatever the number of body portions, 35 each of them is cylindrically bored at 29 to receive a train pipe terminal tube 30 carrying a gasket 31 and enlarged at 32 to provide a shoulder 33. The terminal is threaded at its rear end at 34 and is removable and replaceable through and from the rear of the head. The fitting is surrounded by the 40 spring 35 which abuts at one end against the shoulder 33.

The bore 29 may be enlarged to form a 45 threaded counterbore 36 extending from the back of the head forwardly.

The counter-bore may extend far forward toward the front of the head if desired, and instead of a counter-bore, may extend 50 through the head, with any desired portion or all of the length of collar threaded. If it be a counter-bore it should leave sufficient bore 29' between it and the front of the head to give lateral support to the enlargement 55 32. Two arrangements of this are shown in Figure 2 and in Figure 4, differing in the extent of the counter-bore and cooperating parts and in Figure 5, the enlarged bore passes through the head.

The rear end of the spring 35 is engaged 60 by an inwardly extending shoulder 37 acting as an abutment and carried by a collar 38. The collar extends forwardly beyond the shoulder and has a counter-bore 39 of sufficient diameter to receive a spring and

the outside of the collar is of suitable diameter and is threaded at 40 to fit into the threads of the bore.

The collar 38 can be made adjustable to give varying compressions of the spring 70 for the same gasket position, as in Figure 2, where it is shown in an intermediate position, having a space 41 for further movement and correspondingly extending further 75 outside the head than would be necessary for the position shown; or it can be made to give a predetermined adjustment of this spring compression as in Figure 4.

In Figure 2 the collar is threaded beyond the end of the head to receive a lock nut 43, 80 screwed upon the outside of the collar and abutting against the rear of the head, the threaded portion of the collar extending beyond the lock nut.

Where this form of collar is used, capable 85 of having a nut put on from the rear, it is very desirable to provide the collar with a grip for a wrench or spanner, and a polygonal wrench hold is shown at 44, integral 90 with the collar and smaller than the threaded exterior 40.

Where a predetermined setting of the collar is arranged for, the collar may be provided with an enlarged external wrench-hold 95 as at 44' in Figure 4, in which the enlargement will engage with the rear of the head to take the place in large measure of the nut 43.

The rear end of the terminal 30 is extended 100 so as to pass through the collar to receive the locking nuts 45 and the fitting 46 of or for the normal train pipe. The thread upon the end of the terminal is tapered, corresponding to a pipe thread, but communicates at some such point as 47 with a threading of 105 the same pitch and thread contour but of uniform depth, corresponding to a machine thread. The machine thread provides for a full thread engagement for the nuts in any position along it while the pipe thread receives and tightens against the threads of the fitting. The positions of the lock nuts along the length of the terminal 30 determine the extent of normal projection of the terminal 30 beyond the head when no mating 110 head is engaged. The interior of the terminal is provided with wrench-engaging ribs 30'.

In assemblage, the spring, collar and lock 115 nuts are successively placed upon the terminal sleeves 30. The fitting 46 is then connected and the parts are ready for insertion 120 within the head. The length between the shoulder 33 and the fitting 46 is made sufficient so that the lock nuts can be backed, preferably so as to free the spring 35 wholly from compression. If not, it should provide for reducing the compression sufficiently so that the pressure of this spring 125 against the shoulder 37 will not interfere 130

with turning the collar independently of the sleeve terminal 30.

The collar is now screwed into its intended position after which the lock nuts are moved forward and locked to adjust the compression of the spring 35, and the projection of the sleeve and gasket beyond the face. The adjustability of the collar within the head allows change of the position of the collar if the desired spring compression does not coincide with the intended amount of projection beyond the front of the head.

It will be noted that the stops upon the rear of the tube 30 are wholly independent of the fitting 46 making it possible to adjust the extent of projection by the spring not only independently of this fitting 46 but without loosening the air or steam connections. The lock nut 43 makes it possible to retain the sleeve or collar 38 in any position set, the two adjustments thus permitting normal spring compression of any desired amount with normal uncoupled projection to any desired extent.

In Figure 5 the collar 38 is extended to form not only a long threaded engagement with the head, receiving a part of the length of the spring, but is further extended to the front of the head to form also the guide for the enlarged portion 32, of the terminal 30. This has a decided advantage in making the front of the collar effective as the engaging portion of the head which meets the corresponding portion of the mating head; so that in case of wear this collar can be turned to vary the part receiving the wear, or can be adjusted in order to give or to maintain the desired extent of projection, or can be replaced where excessive wear has taken place.

By reason of the independent adjustability of the casings formed by these projecting collars surrounding the individual train pipe terminals, these points of engagement with adjoining connector parts can be set up independently to correct any lack of alignment of the heads. They can be set up to obtain contact and some pressure even when the cars are coupled, though the pressure present at this time would make it difficult to project them to what might be the preferred positions.

It will be evident that various changes may be made by others interested in obtaining part or all of the advantage of my invention without copying it; and it is my purpose to include herein all such changes as come within the reasonable spirit and scope of my invention.

Having thus described my invention what I claim as new and desire to secure by Letters Patent is:

1. In an automatic train pipe connector, a connector head having an opening there-through, a metallic train pipe terminal

adapted to move within the opening and to be removed rearwardly therefrom, a gasket carried by the terminal and normally projected from said head, a spring surrounding said terminal, a collar threaded into said head, spaced radially at its forward end from said terminal and surrounding the spring, the removal of the collar permitting removal of the terminal, shoulders upon the terminal and collar respectively engaging opposite ends of the spring, a nut threaded upon the exterior of the collar to lock it in adjusted position, threads upon the rear end of the terminal, and lock nut devices for limiting the forward movement of the terminal with respect to the collar and head.

2. In an automatic train pipe connector, a connector head having an opening there-through, a metallic train pipe terminal adapted to move within the opening and to be removed rearwardly therefrom, a gasket carried by the terminal and normally projected from said head, a spring surrounding the terminal, a collar threaded into said head spaced radially at its forward end from said terminal and surrounding the spring, the removal of the collar permitting removal of the terminal, shoulders upon the terminal and collar respectively, a nut threaded upon the exterior of the collar to lock it in adjusted position, threads upon the rear end of the terminal, lock nut devices for limiting the forward movement of the terminal with respect to the collar and head, and a train pipe connector fitting mounted upon the rear end of the terminal and spaced from the lock nut devices to permit backing off of these lock nut devices to provide for adjustment of the forward position of the terminal.

3. In an automatic train pipe connector, a connector head having an opening there-through, a metallic train pipe terminal adapted to move within the opening and removable from the rear, a gasket carried by the terminal and normally projected from said head, a collar threaded into said head, adjustable therein and spaced at its forward end radially from said terminal, the removal of the collar permitting removal of the terminal, a spring surrounding the terminal lying within said space, spring engaging shoulders upon the terminal and collar respectively and a nut threaded upon the exterior of the collar to lock it in adjusted position.

4. In an automatic train pipe connector, a connector head having an opening there-through, a train pipe terminal movable in said opening, having a rearwardly facing shoulder and rearwardly removable from the opening, a gasket carried by the terminal, a spring surrounding the terminal, a collar surrounding the spring and having a forwardly facing shoulder abutting the spring,

- threads upon the outer end of the collar, corresponding threads in an opening in the head larger in diameter than the terminal, within which threads the threads of the collar are adjustable to adjust the position of the collar in the opening and a nut mounted upon the collar, placeable thereon from the rear and adapted to lock the collar in adjusted position.
5. In an automatic train pipe connector, a connector head having an opening therethrough, a train pipe terminal movable in said opening, having a rearwardly facing shoulder and rearwardly removable from the opening; a gasket carried by the connector, a spring surrounding the terminal, a collar surrounding the spring and having a forwardly facing shoulder abutting the spring, threads upon the outer end of the collar engaging corresponding threads in an opening in the head larger in diameter than the terminal, a nut mounted upon the collar, placeable thereon from the rear and adapted to lock the collar in position, threads upon the rear of the terminal, a fitting engaging the threads at the rear and lock nuts upon the terminal, spaced from the fitting and limiting the forward movement of the terminal by engagement with the rear of the collar.
10. In an automatic train pipe connector, a connector head having a bore therethrough and a threaded counter-bore in the rear of the bore, a metallic train pipe terminal having an enlarged forward end fitting the bore, reduced rearwardly therefrom to provide a rearwardly facing shoulder and rearwardly removable from the head, a gasket carried by the terminal, a spring surrounding the reduced portion of the terminal and engaging the shoulder, a collar threaded to fit within the counter-bore, having the forward part
15. of the collar surrounding the spring and provided with a forwardly facing, inwardly extending shoulder engaging the rear of the 45 spring, means for locking the collar in its adjusted position within said counter-bore, and means engaging said terminal for limiting forward movement of the terminal by engagement with the rear of the collar and 50 rearwardly movable upon the terminal to allow withdrawal movement of the collar.
20. 7. In a train pipe connector, a head having a tubular opening therethrough, a tubular train pipe terminal in the opening and rearwardly removable therefrom, an enlargement upon the terminal, a spring engaging the enlargement, a sleeve surrounding the terminal and spring and threaded into the head, fluid connections for said terminal and 55 an abutment upon the terminal engaging the rear of the sleeve and limiting movement of the terminal within the sleeve, rearwardly movable upon the terminal to permit backing out of the sleeve to release the 60 spring while the head engages a corresponding head while maintaining fluid connection with the terminal.
25. 8. In a train pipe connector, a head having an opening therethrough, counter-bored at 70 the rear, a train pipe terminal therein, removable rearwardly therefrom and having an enlarged portion fitting the smaller bore of the opening, a spring about the terminal, a sleeve threaded into the counterbore and 75 surrounding the spring and bearing against the rear of the spring, and an adjustable stop upon the terminal rearwardly movable while the terminal is connected to another terminal by engagement of meeting connectors, to release the spring and permit withdrawal of the sleeve.
30. 80

EDWARD A. ROBINSON.
